Primary Examiner — Elizabeth Albert(74) *Attorney, Agent, or Firm* — Richard B. Cates(57) **CLAIM**

The ornamental design for a can opener, as shown and described.

DESCRIPTION

FIG. 1 is a perspective view from front right of a can opener showing my new design.

FIG. 2 is a bottom view.

FIG. 3 is a left view.

FIG. 4 is a right view.

FIG. 5 is a side view.

FIG. 6 is an opposite side view from that shown in FIG. 5; and, FIG. 7 is a top view.

The broken lines in the drawings are included for the purpose of showing portions of the can opener that form no part of the claimed design.
